US00D985555S

(12) **United States Design Patent** (10) **Patent No.:** **US D985,555 S**
He et al. (45) **Date of Patent:** **** May 9, 2023**

(54) **SMARTWATCH**

(71) Applicant: **SHENZHEN DO INTELLIGENT TECHNOLOGY CO., LTD.**, Shenzhen (CN)

(72) Inventors: **An He**, Shenzhen (CN); **Beijie Hong**, Shenzhen (CN)

(73) Assignee: **SHENZHEN DO INTELLIGENT TECHNOLOGY CO., LTD.**, Shenzhen (CN)

(**) Term: **15 Years**

(21) Appl. No.: **29/825,450**

(22) Filed: **Feb. 1, 2022**

(51) LOC (14) Cl. **14-02**

(52) U.S. Cl. **D14/344**

(57) **CLAIM**

The ornamental design for a smartwatch, as shown and described.

DESCRIPTION

FIG. 1 is a front, right and top side perspective view of a smartwatch showing our new design;

FIG. 2 is a rear, left and bottom side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of portion '9' in FIG. 1; and,

FIG. 10 is an enlarged view of portion '10' in FIG. 2.

The dot-dash lines encircling portions of the smartwatch in FIGS. 1, 2, 9, and 10 are included to show a partially enlarged view only and form no part of the claimed design. The broken lines shown in the drawings represent portions of the smartwatch that form no part of the claimed design.

1 Claim, 10 Drawing Sheets
